UNITED STATES PATENT OFFICE.

ROBERT BIQUARD, OF PARIS, FRANCE, ASSIGNOR TO HIMSELF, HENRI CHERON, AND HENRI DOMINICI, ALL OF PARIS, FRANCE.

APPARATUS APPLICABLE FOR ILLUMINATING CAVITIES OR SURFACES.

1,143,682.

Specification of Letters Patent. Patented June 22, 1915.

Application filed June 11, 1913. Serial No. 773,042.

To all whom it may concern:

Be it known that I, ROBERT BIQUARD, engineer, a citizen of the Republic of France, residing at Paris, France, have invented certain new and useful Improvements in Apparatus Applicable for Illuminating Cavities or Surfaces, of which the following is a specification.

This invention relates to a system which allows of obtaining in a very small compass an intense source of light capable of powerfully illuminating a surface or a cavity without causing any considerable heating therein or thereon.

15 The principle of this system consists in the employment of a refractory rod of rare earth raised to incandescence by an electric current and disposed in a double inclosure or jacket in which circulates a current of water or of a solution capable of absorbing the heat rays. The luminous rod employed is such as those used in Nernst lamps. It is used in preference to metallic filaments (although metallic filaments may be used), be- 25 cause in spite of its small length (2 to 4 centimeters) the rod of rare earth when hot possesses sufficient resistance to withstand the usual voltages of electric mains, say 110 to 220 volts. A metallic filament would 30 need to be 15 to 30 times as long. The rod receives the current in the neighborhood of its two ends by platinum wires which are entirely sheathed in fine tubes of quartz or other material of like refractory and insu- 35 lating character. A tube of quartz or other material as refractory as quartz serves for introducing the luminous rod into its sheath and for insulating from each other the two wires that supply the current to the rod.

40 The drawings accompanying this specification illustrate my invention.

Figure 1 is a view partly in elevation and partly in central section of the interior parts of one form of my improved lamp; Fig. 2 is a similar view of another form; Figs. 3 and 4 are broken away views of a form of lamp employing a plurality of refractory rods; these views are shown at approximately right angles to each other; Fig. 5 is a view partly in elevation and partly in central section of one form of my improved apparatus; Fig. 6 is a longitudinal section of a form of water jacket; Fig. 7 is

a cross-section of the device shown in Fig. 6; and Fig. 8 illustrates another form of arrangement of jacket or outer tube.

Fig. 1 of the accompanying drawings represents a straight rod together with the sheathed platinum wires that serve to supply the current thereto. A is the rod to be raised to incandescence. This receives the electric current by means of the platinum wires a b fitted in tubes or sheaths c d. B is a tube of quartz serving as a support.

Fig. 2 represents a curved rod having its two poles adjacent to each other. In this case also the current is supplied with the aid of two platinum wires sheathed or enclosed in quartz.

Figs. 3 and 4 are views at right angles to each other showing a construction with two rods A disposed side by side, three rods might be employed if desired. These rods are mounted as follows:—A central tube e has a slightly enlarged head f provided with two lateral openings g h through which pass the platinum wires a a that connect the rods to one of the electrodes. These platinum wires pass out through the opening i, where they are attached to a platinum wire j connected to one of the poles of the circuit. The other ends of the rods A are inserted into small funnels k terminating in tubes containing the platinum wires b that connect the rods to the second electrode. The cooling liquid is caused to flow or circulate around a quartz tube C (see the examples Figs. 5, 6, 7 and 8) closed at one end and of a diameter just sufficient to admit the luminous rod A and its attachments. The exterior space in which the cooling liquid circulates may be of various forms.

Fig. 5 shows an arrangement of tubular form and suitable for introducing the light into a cavity. The double inclosure or cooling jacket is in this case formed of two concentric tubes C D, the inner of which C is of quartz and the outer one D of glass or quartz. One of these tubes may be partly silvered if it is desired to localize the luminous emission to a certain region of the tube. The cooling liquid is admitted by a tube m extending to the end of the outer tube, and issues by a tube n. These tubes m and n may be of glass or of thin metal.

Figs. 6 and 7 show respectively in vertical

and horizontal section an example of construction intended for sending the whole of the light on to a small plane surface. For this purpose the outer jacket is formed of a 5 casing σ entirely of glass and in one piece. This casing affects the form of a paraboloid having two flat sides or walls, and near the side or wall which is of smaller diameter are branched two nipples or connections m n for establishing a supply or circulation of 10 water. The upper tubular portion p on which is branched the lateral pipe or nipple n for the outlet of the water is extended upward to receive the luminous device which 15 is thus kept parallel to the side or wall q of the casing σ . Hermetic mounting of the luminous device in the tubular portion p is insured by a metallic screw joint r . This apparatus is silvered all over its outer surface 20 with the exception of the front surface s . The whole of the parabolic surface of the glass casing and its back wall q form reflecting surfaces which direct to the front wall of the casing the light rays cooled by 25 the water flowing or circulating through the casing. As the transparent front wall s of the said glass casing forms part of the casing itself, there is no joint at its periphery. This apparatus can be readily sterilized. 30 The silvering of this apparatus is applied on the outer surface and preferably in the following manner in order to provide a perfectly smooth and very strong and durable reflecting surface economically: A coating 35 of silver is first deposited in the way usual for silvering mirrors, and a coating of any desired thickness is galvanically deposited upon this layer of silver. This method has the advantage not only of consolidating the first layer of silver but of 40 strengthening the glass itself, so that the casing is not fragile.

Fig. 8 represents a form inclosing jacket or casing intended for directing all the 45 light to the conical extremity v by reflection from the conical reflecting surfaces t u . The jacket or casing in which the cooling liquid circulates is bounded internally by the quartz tube C and externally by a tube 50 E of glass or quartz of cylindro-conical form, silvered over the part u . The liquid is led to the end v by a small tube x passing through the cone t .

For using the various devices before described it is necessary on starting to raise the rod of refractory earth to incandescence by some external heating means. The rod is withdrawn from the quartz tube for this 55 purpose and is reinserted into same when it is sufficiently incandescent to have become a conductor.

The cool source of electric light provided as hereinbefore described is particularly suitable for illuminating natural and pathological cavities, and for phototherapy,

luminous projection by transparency or reflection and illuminating microscopes or ultramicroscopes.

In cases where it is not necessary to produce great luminous intensity (say up to 10 70 or 20 candle power for example) and where the total size of the apparatus may be fairly large, a metallic filament may be employed instead of the filament of rare earth. This substitution could not be made if the luminous intensities required were considerable or if the sheath of the filament had to be very small because the relatively rapid blackening of this sheath or tube due to the volatilization of the metal would necessitate 75 too frequent replacement of the lamps or at least cleaning of the same, which would be expensive owing to the necessity for producing the vacuum again. It is not so with the filament of rare earth, as this only produces an insignificant deposit on the sheath or tube with high luminous intensities, and this deposit can be easily removed by cleaning, as the filaments can be withdrawn and replaced without a special operation. 80

What I claim and desire to secure by Letters Patent is:—

1. In a device of the character specified the combination with a pair of quartz tubes, a rod of refractory oxid carried by said tubes, electric wires disposed in the tubes and connected to the said rod, and a support for said tubes. 95

2. In a device of the character specified the combination with a pair of quartz tubes, a rod of refractory oxid carried by said tubes, electric wires disposed in the tubes and connected to the said rod, a support for said tubes, and a quartz tube closed at one 100 end and of a diameter just sufficient to admit the rod and its associated parts. 105

3. In a device of the character specified the combination with a pair of quartz tubes, a rod of refractory oxid carried by said tubes, electric wires disposed in the tubes and connected to the said rod, a support for said tubes, a quartz tube closed at one end and of a diameter just sufficient to admit the rod and its associated parts, and a water jacket surrounding the said quartz tube. 110

4. In a device of the character specified the combination with a pair of quartz tubes, a rod of refractory oxid carried by said tubes, electric wires disposed in the tubes and connected to the said rod, a support for said tubes, a quartz tube closed at one end and of a diameter just sufficient to admit the rod and its associated parts, a water jacket surrounding the said quartz tube, and means for maintaining a circulation 120 through said jacket. 125

5. In a device of the character specified the combination with a pair of quartz tubes, a rod of refractory oxid carried by said tubes, electric wires disposed in the tubes 130

and connected to the said rod, a support for said tubes, a quartz tube closed at one end and of a diameter just sufficient to admit the rod and its associated parts, and a water jacket surrounding the said quartz tube, said jacket having portions of its surface reflectory.

6. In a device of the character specified the combination with a pair of quartz tubes, 10 a rod of refractory oxid carried by said tubes, electric wires disposed in the tubes and connected to the said rod, a support for said tubes, a quartz tube closed at one end and of a diameter just sufficient to admit 15 the rod and its associated parts, and a water jacket surrounding the said quartz tube,

the internal wall forming the water jacket being of a single piece of glass, a portion thereof being of parabolic formation, the conical surfaces being reflective, and the portion of the inclosing quartz tube adjacent the refractory rod position being located in such position that a large body of cooling fluid will surround the same and the light will be reflected outwardly.

In witness whereof, I have hereunto signed my name in the presence of two subscribing witnesses.

ROBERT BIQUARD.
